PISTON VALVE PACKING

Henry E. Muchnic, Atchison, Kans., assignor to
The Locomotive Finished Material Company,
Atchison, Kans., a corporation of Kansas

Application January 24, 1934, Serial No. 708,079

2 Claims. (Cl. 309—29)

My invention, more specifically stated, relates to a one piece steam distribution valve more especially intended for use in the steam chests of locomotives; the invention having for its object 5 the provision of a lighter valve than heretofore whereby the reciprocating load on the valve operating mechanism is reduced.

Another object of the invention is the provision of a valve provided with an integral wear 10 resisting riding shoe or facing in conjunction with flexible or sectional packing rings or sectional ring assemblage.

These objects and the advantages resulting therefrom will be more fully comprehended from 15 the detailed description of the accompanying drawings, wherein:

Figure 1 shows one end of my improved valve in elevation; an intermediate part of the valve broken away, and the other end shown in section. 20

Figure 2 is a sectional elevation of a segmental portion of an end of the valve and taken substantially on the line 2—2 of Figure 1.

Figure 3 is a detail sectional view of one of 25 the valve heads showing a modified form of sectional ring assemblage.

Figures 4, 5, 6 and 7 are similar views each showing a modification of sectional ring assemblage.

Figure 8 is a perspective view of one end of 30 the valve with portions thereof shown in section and a portion of one of the rings broken away.

Figure 9 is a detail cross sectional view of a 35 portion of the valve head disclosing the type of sectional ring assemblage shown in Figures 1, 2 and 8.

The invention, as exemplified in Figure 1, 40 comprises a one piece valve composed of the intermediate tubular portion 10, of predetermined length and diameter, and terminating in the integral heads 11 and 12; that is to say the body of the valve consists of a single piece as shown in Figure 1. The ends or heads are of predetermined diameter and width.

The end or head 12 is internally provided with a sufficient number of spokes 13 formed integral with the inner perimeter of the head and at their inner ends terminating in a hub portion 14. The 45 hub 14 is centrally provided with an opening which receives the enlarged or head-end 15 of the valve-stem or rod 16 of which only a portion is shown. The rod 16, adjacent to the hub 14, is shown threaded to receive a suitable nut 17 and lock-nut 18, whereby the hub is firmly 50 55

clamped between the rod-head 15 and the nut 17. With the valve body composed of a single, rigid piece, the valve-stem or rod 16 need not extend through the length of the valve as in constructions heretofore employed, and hence 5 the weight of the valve is materially reduced and at the same time possibility of play is eliminated.

My single piece valve body provides a lighter construction and hence less wear on the valve gear and on the valve chamber bushing will be 10 encountered as well as less wear on the weight supporting elements or packing elements of the valve results and hence a longer lived valve is provided requiring less frequent renewal of the packing.

In the particular exemplifications the valve-heads or ends 11 and 12 are provided with two 15 parallelly arranged and spaced apart channels as at 19; the channels at one of the sides being undercut to provide the internal lip or shoulder 20 as at 20. The bottoms of the channels 19 in the construction shown in Figure 1 are provided with annular grooves 21.

The grooves 21 in the structure shown in Figure 1 are intended to receive the expander rings 25 or springs 22, which, in this instance, are circular in cross-section; the springs 22 being disposed beneath the bottoms of the channels 19.

The channels 19 are provided with sectional 30 packing rings 23. The various segmental sections at their inner perimeters are provided with the laterally disposed enlargements or heads 24. The width of the channels 19 above the lips or shoulders 20, namely between the outer perimeter of the valve-heads and the lips or shoulders 35 20, is sufficient to permit the enlarged inner perimeters of the ring-segments to be inserted into the channels.

The distance between the bottoms of the channels and the lips or shoulders 20 is greater than 40 the thickness of the enlargements or heads 24 of the sectional rings 23, thus permitting the sectional packing rings to be distended through the action of the expanding springs 22.

In order to hold the packing ring sections in 45 the channels, I provide the snap or spreader rings 25 which are inserted along one of the sides of the packing rings, that is to say in the side of the channel which is not undercut or provided with the annular lip or shoulder 20. 50 The snap rings 25 are of radial dimensions substantially equivalent to the radial distance between the heads of the ring segments and outer perimeter of the packing ring so that the outer perimeters of the snap rings will not extend be- 55

yond the outer perimeters of the packing rings 23. The snap rings 25 are of sufficient thickness to cause one side of the enlargements or heads of the packing rings to remain in the undercut portion, namely beneath the lips or shoulders 20.

In order to prevent the snap rings 25 rotating, these rings, at a convenient point, preferably at the split in the rings, are each provided with a 10 cut-out portion or notch, as at 26 in Figure 2, to receive a dowel 27 inserted transversely in a suitable hole in the adjacent side of the head of the valve.

The heads 11 and 12 of the valve between 15 the spaced apart grooves in each head are provided with relatively wide channels which are filled with wear resisting shoes or bands 28; the shoes or bands being made of a suitable wear resisting metal such as bronze and the like; and 20 these bands are preferably integrally secured to the valve-heads.

In Figure 3, which is a detail sectional view of a portion of a valve-head, the valve head is shown provided with the parallelly arranged and 25 spaced apart channels 29, 29. In this modification the channels are undercut on both sides so as to provide the inner lips or shoulders 30, 30 in both side walls of each channel.

The packing ring assemblage consists of two 30 sectional rings in each channel; the ring sections being somewhat L-shape in cross-section as shown at 31, with the base or laterally disposed portion at the inner perimeters of the ring sections located in the bottom of the channels so 35 that the laterally disposed portions of the packing ring sections will lie in the channels beneath the lips or shoulders 30 and the ring sections prevented from moving out of the channels; the distance between the lips or shoulders 30 40 and the bottom of the channel, however, being considerably greater than the thickness of the laterally disposed base or flange of the packing ring so as to permit radial outward movement of the packing ring sections, as is clearly apparent from the construction shown.

The two packing rings in the same channel are maintained in spaced relation with each other by the split or spreader ring 32, which is of such thickness that the packing rings will be 50 held adjacent the side walls of the channel so that the laterally disposed bases of the packing rings will be held beneath the lips or shoulders 30, 30, as shown, thereby preventing the packing rings from moving too far out of the channels and 55 from dropping out in the event of breakage.

In order to maintain the sectional packing rings and the spreader rings in their proper pre-arranged relation, I insert dowels as at 33 through suitable holes in the packing rings, while 60 the split or spreader rings are grooved or notched on their inner perimeters as shown at 26 in Figure 2. This enables the packing rings to be inserted into the channels 29 and the two rings then spread apart and the spreader ring 32 65 then put into place.

Before the packing ring assemblage is put into the channels, the expander rings 34 are first put into the channels; the expander rings 34 in this instance being preferably in the nature of flat 70 springs of width sufficient to engage with both sectional rings of the assemblage so as to cause the sections of both rings of the assemblage to move radially in unison.

The circumferential face of the valve-head, 75 intermediate of the two channels 29, 29, is also

preferably provided with a wide channel which, like the structure of Figure 1, is provided with a wear resisting shoe or band 28 of suitable wear resisting metal which is integrally secured in place.

In Figure 4, which shows a similar section of a valve-head, the end or head portion of the valve is shown provided with a pair of channels 35 having straight side walls; each channel having a pair of juxtaposed sectional rings 36, 36; 10 the sections of the two rings being held in their prearranged relation by means of a dowel 37 which passes laterally through the adjacent sections.

The ring sections at their outer perimeters and 15 on what may be called the outer sides are provided with the laterally disposed lips 38 which extend over the perimeter of the valve-head which in the particular exemplification is grooved on opposite sides of the channels to receive the lips 38.

The bottoms of the channels are shown provided with the flat springs or expander rings 34, disposed beneath each ring 36 so as to cause 20 the latter to become distended at the same time; 25 the springs 34 being inserted in the channels 35 before the packing rings are inserted.

The portion of the perimeter of the valve-head intermediate of the two channels 35 is shown provided with a wide channel in which a shoe 30 or band 28 of wear resisting metal is integrally secured.

In Figure 5, the section of valve-head there shown is provided with a pair of laterally spaced apart channels 19, substantially similar to those 35 shown in Figure 1 and undercut on one side to provide the shoulders 20; while the bottoms of the channels are also provided with the annular grooves 21. These grooves are provided with the springs or expanders 22, 22 like in 40 Figure 1.

The channels are each provided with a ring composed of segments 39, L-shape in cross-section with the base disposed in the bottom of the channel and the base of the ring extending 45 substantially throughout the width of the channel.

Each channel also has a segmental ring 40 which rests on the base of the segmental ring 39. The base of the ring 40, at one side, is provided with a laterally disposed lip 41 which is adapted to extend beneath the shoulder 20 on the side wall of the channel when the ring 50 assemblage is in position.

The two segmental rings 39 and 40 are maintained in lateral spaced relation by a spreader ring 42. With the rings 40 resting on the bases of rings 39, it is apparent that the expander springs 22 will cause both rings to be distended.

The valve, like in the other constructions, is 60 also provided with a wear resisting band or shoe 28 preferably integrally secured to the valve-head.

In the detail sectional view Figure 6, the valve-head is also provided with a pair of parallelly 65 arranged and spaced apart channels 43, substantially similar to those shown in Figure 4, except possibly for depth; and these channels are each provided with segmental rings 44 of similar construction, in side to side relation and 70 without lips. The abutting sides of the ring segments are provided with semi-cylindrical grooves 45, 45, to receive the round expansion spring 46; while one pair of segments in the bottoms of these grooves are bored to receive the 75

head or cross-pin 47 formed at one end of the split expander ring 46. This not only ensures the spring being maintained in proper position, but it also maintains a prearranged relation of 5 the joints between the segments of one ring 44 and the joints of the other ring 44 so that the joints of the two rings are not capable of shifting so as to register.

This structure is similar to that disclosed in 10 my patent No. 1,572,443.

The valve-head intermediate of the two sets of packing rings is also channeled and provided with the wear resisting shoe or band 28.

Figure 7 shows a section of valve-head with a 15 pair of channels 43, spaced apart and each provided with plain sided sectional packing rings 48; the segments of both rings being similar and both rings resting on the flat expander or spring 34; while the valve-head outer perimeter, intermediate of both channels 43, is also preferably provided with a wear resisting band or shoe 28 integrally secured in a wide channel in the valve-head.

With my improved structure, wherein the 25 heads or ends and the intermediate tubular body portion are all made in one piece, it is apparent that the possibility of steam leaks is eliminated which, however, is not the case with the composite type heretofore employed wherein leaks 30 between the follower and the bull-ring and between the bull-ring and the spool and between the spool and the follower are possible, especially when the connections between the two followers or spiders become loose. At the same time a

very much lighter valve is provided and hence the reciprocating load lightened and consequently wear considerably reduced. Furthermore, wear is also further lessened by the application of a band of wear resisting metal around the 5 valve-heads or ends.

I have described my invention as a steam distribution valve, although it is apparent that the invention is applicable to means of that general character as for example steam pistons and the like; the expressions employed being merely terms of description and not terms of limitation.

What I claim is:

1. In a steam distribution valve the head portion whereof is provided with a ring-receiving 15 channel, a packing ring assemblage in said channel consisting of a sectional ring and a one piece ring, the ring sections having laterally disposed portions, while the one piece ring is self-expansive and is disposed in a circumferential 20 plane coincident with said laterally disposed portions whereby outward movement of the sectional ring is limited when the assemblage is removed from a cylinder, the relation between the ring sections and said one piece ring being 25 such that the outer perimeters of the sectional ring and of the one piece ring will lie flush with the cylinder walls; and an expander located in said channel beneath the assemblage.

2. A segmental packing ring provided with a 30 continuous circumferential groove, an expander beneath the ring, and an expansible packing ring adapted to seat in said groove.

HENRY E. MUCHNIC.
